CLAIM

The ornamental design for a whimsical flying avian, as shown and described herein.

DESCRIPTION

FIG. 1. Is a bottom plan view of my whimsical flying avian; FIG. 2. Is a top plan view thereof; FIG. 3. Is a left side elevational view thereof with the right side elevational view being a mirror image thereof; FIG. 4. Is a rear elevational view thereof; and, FIG. 5. Is a front elevational view thereof. The portions shown in broken lines in FIG. 3 are for illustrative purposes only and form no part of the claimed design.
